 tion of Massachusetts

Application December 15, 1942, Serial No. 469,085

6 Claims. (Cl. 51—72)

The invention relates to grinding machines and more particularly to a cylindrical type grinding machine adapted for successively grinding a plurality of shouldered portions on a work piece.

One object of the invention is to provide an improved hydraulically operated shouldered type grinding machine for precisely grinding a plurality of spaced shoulders on a work piece. Another object of the invention is to provide a multiple stop feeding mechanism for precisely feeding the grinding wheel for grinding a plurality of spaced shoulders of different diameters. Another object of the invention is to provide a hydraulically actuated electrically controlled feeding mechanism having a plurality of stops or gauge blocks in which an electrical interlock is provided to prevent initiating an infeeding movement of the grinding wheel except when a predetermined gauge block is in an operative position. A further object of the invention is to provide a work table stop mechanism which is interlocked with the feed control so that the work table may be precisely positioned for grinding a predetermined shoulder on the work piece. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of an improved grinding machine embodying this invention;

Fig. 2 is a fragmentary front elevation on an enlarged scale of the control lever and table positioning dog mechanism;

Fig. 3 is a fragmentary piping and wiring diagram, showing the hydraulically operated system for controlling the feeding movement of the grinding wheel together with the electrically operated control mechanism therefor;

Fig. 4 is a fragmentary sectional view taken approximately on the line 4—4 of Fig. 3;

Fig. 5 is a fragmentary rear elevation on an enlarged scale, of the feed stop mechanism;

Fig. 6 is a fragmentary cross sectional view, on an enlarged scale, taken approximately on the line 6—6 of Fig. 5;

Fig. 7 is a fragmentary cross sectional view, approximately on the line 7—7 of Fig. 3, taken through the control lever and showing the limit switch actuated thereby; and

Fig. 8 is a fragmentary elevation partly in section of the parts shown in Fig. 5 showing the relationship between the feed gauge blocks and the hydraulically operated feed mechanism.

A grinding machine has been illustrated in the drawings comprising a base 10 which supports a longitudinally traversable work supporting table 11. The work supporting table 11 is arranged to slide transversely on a flat way 12 and a V way (not shown) formed on the upper surface of the base 10. The work supporting table 11 serves as a support for a headstock 13 and a footstock 14 which are provided with work supporting centers 15 and 16 respectively. The work supporting centers 15 and 16 serve rotatably to support a work piece 17 having a plurality of shouldered cylindrical portions to be ground.

The base 10 also serves as a support for a transversely movable wheel slide 20. The wheel slide 20 rotatably supports a wheel spindle 21 in suitable bearings (not shown). A grinding wheel 22 is mounted at one end of the wheel spindle 21. The grinding wheel 22 is preferably driven by an electric motor 23 which is mounted on the upper surface of the wheel slide 20. A driving pulley 24 is mounted on the outer end of a motor shaft 25. The pulley 24 is preferably a multi-V-groove pulley which is connected by a multi-V belt 26 with a multiple V groove pulley 27 mounted on the right hand end of the wheel spindle (Fig. 1). The wheel slide 20 is arranged to slide transversely relative to the base 10 on suitable flat and V ways (not shown) which is a well known and common feature in the grinding art.

The work supporting table 11 may be traversed longitudinally by means of a manually operable traversing mechanism comprising a manually operable traverse wheel 30 which is supported on the outer end of a shaft 31. The inner end of the shaft 31 is provided with a gear 32 which meshes with a gear 33 mounted on a rotatable shaft 34. The shaft 34 also carries a gear 35 which meshes with a rack bar 36 depending from the underside of the work table 11. It will be readily apparent from the foregoing disclosure that the rotation of the hand wheel 30 will be imparted through the gear mechanism just described to traverse the table 11 longitudinally in either direction, the direction of movement of the table being determined by the direction of rotation of the traverse wheel 30.

If desired, the table 11 may be traversed or reciprocated longitudinally by a hydraulically operated mechanism comprising a hydraulic cylinder 40 which is fixedly supported on the under side of the table 11. The cylinder 40 contains a pair of pistons 41 and 42. The pistons 41 and 42 are connected by hollow piston rods 43 and 44 respectively with hollow brackets 45 and 46 respectively which are in turn fixedly mounted on the opposite ends of the base 10.

A reversing lever 47 is supported on a rock shaft 48 which is connected to actuate a control valve (not shown) located within the machine

base 10. A manually operable stop and start lever 49 is also mounted on the front of the machine base and is arranged to actuate a stop and start valve (not shown) to stop and start the traversing or reciprocating movement of the work supporting table 11. The details of this hydraulic traversing or reciprocating mechanism have not been illustrated in the present case and this mechanism is substantially identical to that shown in the prior United States patent to Wallace H. Wood, No. 2,071,677 dated February 23, 1937, to which reference may be had for details of disclosure not contained herein. A pair of reversing dogs 50 and 51 are adjustably supported by a T-slot 52 formed in the front edge of the work supporting table 11.

Wheel feeding mechanism

A wheel feeding mechanism is provided for controlling the infeeding movement of the grinding wheel 22. The wheel slide 20 is provided with a depending half nut 55 which meshes with a rotatable cross feed screw 56. The feed screw 56 is rotatably supported at one end by a bearing 57 which is supported in fixed relationship to the base 10. The other end of the feed screw 56 is rotatably journaled in a slidably mounted bearing member 58 which is slidably keyed within a cylindrically shaped aperture 59 formed within the base 10 of the machine. The feed screw may be rotated manually for adjusting the position of the grinding wheel slide 20 in setting up the machine by means of a manually operable feeding mechanism to be hereinafter described.

A reduced forward end portion 60 of the feed screw 56 is slidably keyed within a rotatable sleeve 61 which is fixedly connected to a shaft 62 which supports a gear 63. Gear 63 meshes with a gear 64 mounted on the inner end of a shaft 65 the outer end of which supports a manually operable feed wheel 66. By rotation of the feed wheel 66, the screw 56 may be rotated in either direction to cause the grinding wheel 22 and its supporting slide to move either toward or from the work piece 17. A stop pawl 67 is pivotally mounted on the front of the machine base and is arranged in the path of a stop abutment 68 to facilitate precisely stopping the infeeding movement of the grinding wheel.

In order that the wheel slide 20 may be rapidly moved toward the work supporting table 11 to grind a work piece 17 by the plunge-cut method, the feed screw is connected to a piston rod 70. A fluid pressure cylinder 71 is formed within the base 10 of the machine and contains a slidably mounted piston 72 which is connected with or formed integral with the piston rod 70. As illustrated in Fig. 3, the other end of the piston rod 70 is fixedly connected to the slidably mounted bearing member 58 so that when fluid under pressure is admitted to either end chamber of the cylinder 71, the endwise movement of the piston rod 70 will be transmitted to produce an axial endwise movement of the feed screw 56 which in turn transmits this motion to produce a transverse feeding movement of the grinding wheel slide 20 and the rotatable grinding wheel 22.

A motor driven fluid pressure pump 74 is arranged to pump fluid through a pipe 75 from a reservoir 76 which is located within the base 10 of the machine. The pump 74 forces fluid under pressure through a pipe 77 to a feed control valve 78. The feed control valve 78 is preferably a piston type valve comprising a valve stem 79

having formed integrally therewith a plurality of valve pistons. In the position of the valve 78 (Fig. 3) fluid under pressure passing through the pipe 77 passes through a passage 80 into a cylinder chamber 81 to move the piston 72 together with the wheel slide 20 and the grinding wheel 22 to a rearward or inoperative position. During the passage of fluid under pressure into the cylinder chamber 81, fluid is exhausted from a cylinder chamber 82 through a passage 83 and out through an exhaust pipe 84 into the reservoir 76.

Similarly when the valve stem is shifted toward the left (Fig. 3), the direction of flow of fluid within the feed cylinder 71 will be reversed. In this position of the valve, fluid under pressure passing through the pipe 77 will pass through the valve 78, through the passage 83 into the cylinder chamber 82 to initiate a movement of the piston 72 toward the left which in turn transmits a movement toward the left of the wheel slide 20 and the grinding wheel 22 to cause an approaching movement of the grinding wheel 22 toward the work piece 17.

The forward end of the valve stem 79 is provided with a spool shaped member 86 which is connected by a pin 87 with a lever 88. Lever 88 is pivotally supported by a stud 89. The lower end of the lever 88 is connected by a stud 90 and a link 91 with a pull type electric solenoid 92. The valve stem 79 is normally held in its right hand end position by means of a tension spring 93 which is connected at one end by a stud 94 with the lever 88 and is connected at the other end to stud 95 which is fixed relative to the base 10 of the machine. When it is desired to cause an infeeding movement of the grinding wheel, the solenoid 92 is energized in a manner to be hereinafter described which serves to rock the lever 88 in a counterclockwise direction to shift the valve stem 79 toward the left to initiate an infeeding movement of the grinding wheel 22.

Dash pot

The piston and cylinder mechanism, above described, serves to cause the grinding wheel 22 rapidly to approach or recede from the work piece. In order to reduce the rapid approaching movement to a predetermined grinding feed, it is desirable to provide a wheel feed controlling or regulating mechanism, such as a dash pot mechanism, including a pair of dash pot pistons 97 and 98 which may be rendered effective when the grinding wheel 22 is about to engage and contact with the surface of the work to be ground. The dash pot pistons 97 and 98 are normally held in a rearward or right hand end position by means of compression springs. During the rapid approaching movement of the grinding wheel 22 the dash pot pistons 97 and 98 are inoperative.

The piston rod 70 extends toward the rear of the machine. A sleeve 99 is adjustably supported on the piston rod 70 and contains a pair of integrally formed diametrically opposed arms 100 and 101 each of which is provided with a boss which are arranged to engage the dash pot pistons 97 and 98, respectively. An adjustable collar 103 is adjustably mounted on a threaded portion 104 formed on the rear end of the piston rod 70. When fluid under pressure is admitted into the cylinder chamber 82 to cause the grinding wheel 22 to move toward the work piece 17, the rapid approaching movement continues until the adjustable collar 103 engages the end of the

sleeve 99. Continued movement of the piston 72 is resisted by the dash pot pistons 97 and 98 which force fluid under pressure from the dash pot cylinders through an adjustable needle valve 105 into a reservoir 106. By adjustment of the needle valve 105, the exhaust of fluid from the dash pot cylinders may be readily controlled to produce the desired infeeding movement so that the grinding wheel 22 will be moved into the work piece 17 to grind the same at the desired rate of speed. This dash pot mechanism is substantially the same as that shown in the United States Patent to R. A. Cole and C. H. Amidon, No. 2,101,790, dated December 7, 1937, and since this feature is not considered to be a part of the present invention, the details of the disclosure have not been completely illustrated and described herein. For details of disclosure not contained herein, reference may be had to the prior patent above mentioned.

Positive stop

In order to grind a work piece 17 to a predetermined size, it is necessary to feed the grinding wheel 22 toward the work piece to grind the same and then to stop the infeed and allow the grinding wheel 22 to grind out or to allow the sparks to die out in order to round up the work so that it will be ground to a true cylindrical surface of a predetermined size. In the present disclosure, the machine as set up is provided with an adjustable stop sleeve 106 which surrounds the sleeve 99 and is held in an adjusted position thereon by means of a lock nut or collar 107. The positive stop sleeve 106 is arranged to engage the end face of the dash pot cylinder head 108 positively to limit the infeeding movement of the wheel slide 20 and the grinding wheel 22.

Multi-stop

It is desirable to provide a multi-stop mechanism for limiting the infeeding movement of the wheel slide 20 so as to limit the infeeding movement of the grinding wheel 22 to facilitate successively grinding a plurality of shouldered portions on the work piece 17 to predetermined sizes. This multi-stop mechanism is preferably arranged so that it may be manually actuated and is preferably interlocked with the table traversing or reciprocating movement of the work table 11 to position successive shoulders in operative relation with the grinding wheel 22. As illustrated in the drawings (Fig. 5) a bracket 110 is fixedly mounted on the rear of the machine base and is provided with a downwardly extending portion having a bearing (not shown) which serves as a support for a rock shaft 111. Rock shaft 111 supports a sector-shaped frame 112. The frame 112 serves as a support for a pair of arcuate shaped members 113 and 114 which form an elongated slot or aperture 115 surrounding the threaded portion of the piston rod 70. The arcuate shaped members 113 and 114 are removably mounted on the frame 112 so that they may be readily interchanged if desired. The arcuate shaped members 113 and 114 serve as supports for a plurality of pairs of stop blocks or gauge blocks 116, 116a, 117, 117a, 118, 118a, 119, 119a, 120 and 120a which are arranged so that they may be successively swung into an operative position between the stop collar 103 and the end of the sleeve 99. The stop blocks or gauge blocks 116, 116a, 117, 117a, 118, 118a, 119, 119a, 120 and 120a are resiliently supported on the arcuate members 113 and 114. The successive pairs are

interposed between the collar 103 and sleeve 99, so as to successively limit the infeeding movement of the grinding wheel 22 to produce shouldered cylindrical portions on the work piece 17 of predetermined diameters.

A manually operable mechanism is provided for shifting the frame 112 successively to position the feed stop or gauge blocks in operative positions comprising a manually operable lever 125 which is mounted on the forward end of a rock shaft 126. The front end of the rock shaft 126 is supported in suitable bearings (not shown) formed in the base 10 of the machine. The rear end of the rock shaft 126 is supported in a bearing formed integral with the bracket 110 which is fastened to the rear of the machine base. A lever 127 is fixedly mounted on the rear end of the shaft 126 and is connected by a stud 128 with one end of a link 129. The other end of the link 129 is connected by a stud 130 with the sector-shaped plate 112. It will be readily apparent from the foregoing disclosure that when the lever 125 is moved in either direction, a corresponding movement will be imparted to the plate 112.

In order to facilitate locating the pairs of stop blocks successively in operative positions, the notched plate 131 is fixedly mounted on the front of the machine base adjacent to its right hand end (Figs. 1 and 3). The plate or bracket 131 is provided with a plurality of notches 132, 133, 134, 135 and 136. In the position illustrated in Figs. 1 and 2, the lever 125a is positioned opposite the slot 134 thus locating the plate 112 with the stop or gauge blocks 118 and 118a in operative position. When it is desired to shift to grind a new shoulder on the work piece 17, the lever 125 may be rocked in either direction to bring it into alignment with successive notches on the plate or bracket 131.

The upper portion of the lever 125 is pivotally mounted so that it may be readily moved into operative engagement with the notches on the plate 131. A pivotally mounted lever 125a is pivotally supported by a stud 137 and is arranged so that the upper end of the lever 125a may be swung into operative engagement with the notches 132 to 136 inclusive when desired.

Table positioning

In order to precisely position the work piece 17 and the work table 11 to precisely locate the successive shoulders on the work piece 17 to be ground, a table stop mechanism is provided comprising a stop dog 138 which is adjustably supported by the T-slot 52 on the front edge of the table 11. The right hand end of the stop dog 138 is provided with a plurality of stepped shoulders or stop surfaces 139, 143 and 141 which are arranged successively to position the work piece 17 and table 11 for grinding shouldered portions 17a, 17b, and 17c respectively on the work piece 17. The notched plate 131 also serves as a support for a plurality of stop studs 142, 143, 144, 145 and 146. These stop pins or studs are normally held in an inoperative position out of the path of the stop dog 138 by compression springs 147 (Fig. 4). When the lever 125 is shifted into the desired position opposite a notch in the plate 131 corresponding to the shoulder on the work piece to be ground, the lever 125a is rocked into engagement with the notch 134 which moves the stop stud 144 toward the right (Fig. 4) so that the stop plunger 144 lies in the path of the shoulder 140 on the dog 138 so as to position the shouldered portion 17b in operative position relative to the grinding wheel 22. After the lever

125a has been shifted into operative engagement with the notch 134, the table 11 may then be moved toward the right into the position shown in Fig. 2 with the stop shoulder 140 of the stop dog 138 in operative engagement with the stop pin 144.

Similarly the lever 125 may be moved in a clockwise direction into operative position with respect to the notches 133 or 135 respectively to facilitate positioning the table 11 for grinding the shouldered portions 17a and 17c on the work piece 17.

Electric feed control

An electrically operated wheel feed control mechanism is provided comprising a manually operable lever 150 which is pivotally supported by a stud 151 on the front of the machine base. When it is desired to initiate an infeeding movement of the grinding wheel, the lever 150 is rocked in a counterclockwise direction to close a switch 152 (Fig. 2) which is arranged to close a circuit to energize the solenoid 92 if the other parts of the mechanism are in an operative position. The closing of the switch 152 also starts an electrical time delay relay 153 which is arranged to control the over-all duration of the grinding cycle, that is, the rapid approach, the slow grinding feed and the period of dwell after the feed has stopped. After a predetermined time interval has elapsed the time relay operates to break the circuit to de-energize the solenoid 92 whereupon the released tension of the spring 93 shifts the valve 78 into the position illustrated in Fig. 3 to cause a rearward movement of the grinding wheel 22. If it is desired to stop grinding at any time during the cycle, the lever 150 may be rocked in a clockwise direction to open a switch 154 thus energizing the solenoid 92 and allowing the electric time delay relay 153 to reset itself on the next operation.

Electrical interlock

It is desirable to provide a suitable interlocking mechanism so that a wheel feeding movement cannot be initiated unless the worktable has been moved to position the predetermined stop plunger in the path of the steps on the stop dog 138a. This interlock may comprise a limit switch 155 which is carried by the control lever 125. The actuating plunger 156 of the switch 155 is normally held down to hold the switch open by means of a lug 157 carried by the lever 125a. The limit switch 155 is a normally closed switch so that when the lever 125a is brought into engagement with a notch on the bar 131, the limit switch will be closed to close an electric circuit. The limit switch 155 is preferably connected in series with the wheel feed starting switch 152 so that if the lever 150 is moved to close switch 152 to initiate an infeeding movement of the grinding wheel, the feeding movement cannot be initiated until lever 125a is moved into an operative position with one of the notches on the bar 131 thus preventing a longitudinal movement of the table 11 while grinding a predetermined shouldered portion on the work piece 17. When the lever 125a has been rocked in a counterclockwise direction (Figs. 3 and 4) into an operative position within one of the notches in the bar 131, the switch 155 closes thus rendering the electric circuit operative so that when the feed control lever 150 is rocked to close the push button switch 152 a circuit will be completed to energize the solenoid 92 to initiate an infeeding movement of the grind-

ing wheel 22 and at the same time to start the time delay relay 153 in operation.

In case it is desired to grind a plurality of steps 17d, 17e, 17f and 17g on the left hand end of the work piece 17 (Fig. 1), a plurality of stop shoulders 160, 161, 162 and 163 are provided on the left hand end of the table stop dog 138. The table 11 may be moved toward the right (Fig. 1) to position the successive shoulders 17d, 17e, 17f and 17g successively in operative position with respect to the grinding wheel 22. The stop studs or plungers 143, 144, 145 and 146 successively are actuated by the control lever 125a to limit the position of the table 11 to facilitate grinding the shouldered portion on the left hand end of the work piece 17.

The operation of the improved grinding machine will be readily apparent from the foregoing disclosure. Assuming all of the mechanisms 15 to have been previously adjusted, a work piece 11 is moved into position on the work centers 15 and 16 and the grinding wheel and work piece are then rotated. The control lever 125a is then shifted into position opposite one of the notches 25 132, 133, 134, 135 or 136 depending upon the shoulders to be ground. The control lever 125a is then moved into engagement with the predetermined notch after which the table start and stop lever 49 is shifted to start the movement of 30 the table toward the right to bring a shoulder on the dog 138 into engagement with the stop stud which has been moved by the lever 125a into an operative position, the direction of movement of the table 11 being determined by the position of 35 the reversing lever 47. During a shoulder grinding operation, the normal table reversing dogs 150 and 151 are moved to inoperative positions out of operative relation with the reversing lever 47. The feed control lever 150 may then be 40 rocked in a counterclockwise direction (Fig. 3) to close the starting switch 152, the switch 155 having been previously closed by actuation of the lever 125a, which serves to energize the solenoid 92 to shift the feed control valve 78 to admit the 45 fluid under pressure in the cylinder chamber 82 to initiate a forward feeding movement of the grinding wheel 22. The forward feeding of the grinding wheel to grind a portion proceeds in the manner above described. At the same time the 50 solenoid 92 is energized, the electrical time delay relay 153 is set in motion to govern the over all infeeding movement of the grinding wheel 22. After the predetermined time interval has 55 elapsed the time relay 153 serves to break a circuit thus de-energizing the solenoid 92 which allows the released tension of the spring 93 to return the feed control valve 78 into the position illustrated in Fig. 3. The feed control valve 78 as illustrated in Fig. 2 admits fluid under pressure to the cylinder chamber 81 to cause a rearward movement of the piston 72, the grinding wheel slide 20, and the grinding wheel 22. After one shoulder on the work piece 17 has been ground to the desired predetermined size, the levers 125a and 125 may be shifted either toward 60 the right or toward the left into an operative position with respect to notches in the notched plate to locate the corresponding pairs of stop blocks 116, 117, 118, 119 or 120 in operative position to 65 govern the necessary infeeding movement of the grinding wheel to grind the next shoulder on the work piece to the desired and predetermined size. The other operations are then completed to grind the second shoulder and the entire cycle of operations is then completed to grind successive 70 75

shoulders on the right hand end of the work piece 17.

It will be readily apparent from the foregoing disclosure that the limit switch 155 serves as an interlock to prevent initiating an infeeding movement of the grinding wheel unless the successive stop blocks 116, 117, 118, 119 or 120 are in operative position to control the necessary infeeding movement of the grinding wheel.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine having a longitudinally movable work supporting table, a transversely movable grinding wheel slide, a rotatable grinding wheel thereon, means to move said table longitudinally to feed said slide transversely including a plurality of feed stops precisely to locate said grinding wheel successively to grind a plurality of spaced shoulders on a work piece, an adjustable table dog, means including a plurality of table locating plungers cooperating with said dog precisely to locate said table successively in predetermined positions for said shoulder grinding operations, and means including a control lever which is arranged when moved in one direction to actuate said feed stops to facilitate grinding a predetermined portion of the work piece to a predetermined size and when moved in another direction to actuate said table locating plungers to facilitate location of a predetermined portion of a work piece in operative relation with the grinding wheel.

2. In a grinding machine having a longitudinally movable work supporting table, a transversely movable grinding wheel slide, a rotatable grinding wheel thereon, means to move said table longitudinally, means to feed said slide transversely, a movable frame, means including a plurality of feed stops on said frame precisely to locate said grinding wheel successively to grind a plurality of spaced shoulders on a work piece to predetermined diameters, an adjustable table dog, means including a plurality of normally inoperative table locating plungers cooperating with said dog precisely to locate said table successively in predetermined positions for said shoulder grinding operations, and an interlock including a manually operable control lever which is movable in one direction to move said frame successively to position said feed stops in an operative position and in a second direction successively to move said table locating plungers into an operative position.

3. In a grinding machine having a longitudinally movable work supporting table, a transversely movable grinding wheel slide, a rotatable grinding wheel thereon, means to move said table longitudinally, means to feed said slide transversely, a pivotally mounted frame, means including a plurality of feed stops on said frame precisely to locate said grinding wheel successively to grind a plurality of shoulders on a work piece, an adjustable stepped dog on said table, means including a plurality of normally inoperative slidably mounted table locating plungers each of

which in an operative position is in the path of one of the steps on said dog precisely to locate said table successively in predetermined positions for said shoulder grinding operations, and an interlock including a manually operable control lever which is operatively connected when moved in one direction to swing said frame successively to locate said feed stops in an operative position and when moved in a second direction successively to move said table locating plungers into operative position with relation to the stepped dog on said table.

4. In a grinding machine having a longitudinally movable work table, a transversely movable grinding wheel slide, a rotatable grinding wheel thereon, means to move said table longitudinally, means including a solenoid to initiate an infeeding movement of the grinding wheel, a plurality of spaced stops successively to limit the infeeding movement of the grinding wheel to facilitate grinding a plurality of stepped shoulders on a work piece, a notched bar having a plurality of notches corresponding with said spaced feed stops, a pivotally mounted support for said stops, a pivotally mounted lever to actuate said stops which is arranged when in an operative position to engage one of said notches, and an interlock including an electric switch which is actuated by movement of said lever into an operative position to energize said solenoid to initiate an infeeding movement of the grinding wheel.

5. In a grinding machine having a longitudinally movable table, a transversely movable grinding wheel slide, a rotatable grinding wheel thereon, means to move said table longitudinally, means including a solenoid to initiate an infeeding movement of the slide, a plurality of spaced stops successively to limit the infeeding movement of the grinding wheel to facilitate grinding a plurality of stepped shoulders on a work piece, a notched bar having a plurality of spaced notches corresponding with said spaced feed stops, a pivotally mounted support for said stops, a pivotally mounted lever to actuate said support and stops which is arranged when in an operative position to engage one of said notches, and an interlock including an electric switch which is actuated by movement of said lever into an operative position to energize said solenoid to initiate an infeeding movement of the grinding wheel only when said lever is in engagement with one of said notches.

6. In a grinding machine having a longitudinally movable work table, a transversely movable grinding wheel slide, a rotatable grinding wheel thereon, means to move said table longitudinally, means including a solenoid to initiate an infeeding movement of the slide, a movable support having a plurality of feed stops successively to limit the infeeding movement of the grinding wheel for grinding a plurality of shoulders on a work piece, a stepped adjustably supported dog on said table, the steps of said dog corresponding with spaced shoulders on a work piece, a plurality of plungers each of which is positioned in the path of one of said steps on said dog, means normally to hold said plungers in an inoperative position, and a pivotally mounted control lever which is arranged so that movement in one direction serves successively to position the feed stops in an operative position and movement in another direction serves to move the corresponding table stop plunger into an operative position.

JOHN I. GARSIDE.
